GRAY STAUNTON, OF MUSKEGON, MICHIGAN, ASSIGNOR TO STAUNTON JAR CORPORATION, OF BUFFALO, NEW YORK, A CORPORATION OF NEW YORK.

CLOSURE MEANS FOR HERMETICALLY-SEALED JARS.

1,212,274.

Specification of Letters Patent. Patented Jan. 16, 1917.

Application filed May 3, 1913, Serial No. 765,186. Renewed June 9, 1916. Serial No. 102,800.

To all whom it may concern:

Be it known that I, GRAY STAUNTON, a citizen of the United States, residing at Muskegon, in the county of Muskegon and State of Michigan, have invented certain new and useful Improvements in Closure Means for Hermetically-Sealed Jars, of which the following is a specification.

My invention relates to improvements in vessels to be hermetically sealed.

One of the objects of my invention is to provide in a vacuum package new and improved means for establishing a hermetically sealed joint between a containing vessel and closure therefor.

More specifically one of the objects of my invention is to so fashion the opening of the package and the coöperating parts of the closure thereof that the packing, or sealing ring, will be so distorted by the effect of pressure, due to the vacuum tendency within the package or vessel as to provide a broken joint or tortuous passage, between the ring and the vessel parts, for the air that may pass into the jar as a result of any defects thereof, thereby more easily and surely to maintain the desired rarefaction, or attenuation, within the vessel.

Another object of my invention is to so form the sealing surfaces of the vessel, and of the cover with which the sealing ring comes in contact, as to be free from crizzles and checks that are usually produced in the surface of molded glass articles at the time when the parts are molded.

Other and further objects of my invention will become apparent to those skilled in the art from a consideration of the following description when taken in conjunction with the drawing, wherein;

Figure 1 is a vertical central section of an all-glass preserving jar or vessel, showing the parts in place, as when sealed. Fig. 2 is a plan view of the jar. Fig. 3 shows the parts in their relative separated position in vertical plane, before being assembled for sealing. Fig. 4 is an enlarged, fragmentary sectional view of a portion of the jar and cover, showing the means for breaking the seal.

In all of the views the same reference characters are employed to indicate similar parts.

In my co-pending application, vacuum packages, and means for sealing the same,

Serial No. 708,965, filed July 12th, 1912, I have shown one means by which a jar of the character about to be described may be sealed, wherein a pump, having a base portion resting upon the upper edge of the jar and overlying the cover, operates as a means for exhausting the air within the jar, while the cover, underlying the pump base, operates as a check valve during the sealing process. Of course my present invention is not limited to the specific means disclosed in my earlier application for the purpose of sealing the vessel, as any means effective for this purpose may be employed.

In the specific embodiment illustrated herein, 5 is a jar, or vessel, preferably of glass, and 6 is the cover, preferably of the same material. The inner surface of the jar opening is provided with an angular ledge or shoulder, 7, the surface of which is at substantially forty-five degrees (45°) to a vertical plane, in which is contained the sealing surface 8. These angularly disposed surfaces comprise the sealing surfaces for the packing ring and in the construction of a machine-molded jar these surfaces are usually free from crizzles, checks or cracks.

The cover or closure 6 is provided with an annular, overhanging flange 9, having right angle annular contact surfaces 10 and 11. These surfaces are also free from crizzles, cracks and checks usually found on salient edges in the manufacture of devices of this character, and for this reason they are well adapted for affording a seat for the packing ring. The ring 12 is preferably made of yielding, compressible material, such as pure rubber, or the like. It is preferably rectangular in cross-section, and is of such diameter as to easily slip over the shoulder 11 of the cover 9, its outer diameter permitting it to pass well within the opening of the largest diameter 8 in the jar 5.

When the jar has been exhausted of air in the process of sealing, the pressure exerted upon the cover 6, due to the outside atmospheric pressure, will force the cover into the mouth of the jar, thereby compressing and distorting the rubber ring 12 into the shape shown in Figs. 1 and 2. The tapered surface 7 of the jar serves to force the ring 12 toward the surface 11 of the cover, thereby compressing the ring 12 between these parts and causing intimate contact therebetween. The upper portion of the

ring 12 is radially expanded by the effect of pressure so as to cause a portion to overlie the sharp angle, or shoulder, at the conjunction of the angle, vertical surface 8 and the 5 longitudinal top surface 13 of the jar.

The wedging effect of the yielding ring 12 is a large factor toward securing a perfect and effective joint between the jar and the cover, and the portion 14 overlying the upper, inner shoulder of the jar, increases the 10 difficulty or impossibility of the air in passing into the jar by the tortuous path thus established.

The over-hanging ledge 9 of the cover 6 is notched as at 15 for access to the sealing ring. To remove the cover 6 it is only necessary to admit air into the jar 5, and to accomplish this a pin 16 may be passed into the notch 15, along the vertical wall 17 of the 15 cover and between said vertical wall and the inner surface of the ring 12, permitting the air to pass between the ring and the vertical wall, through apertures effected by the insertion of the pin 16, the wall 17 serves as 20 a guide for the point of the pin, and permits the pin to be pressed between the said wall and the inner surface of the ring without 25 penetrating the ring.

A vessel once sealed by the means described 30 will remain sealed until the cover is removed in the manner mentioned, and should only a portion of the contents of the vessel be used the vessel may be immediately resealed and the remaining contents thus 35 preserved for further use.

The device disclosed is sanitary and very efficient, all parts being made of glass except the packing ring, and new packing rings may be used with each successive use 40 of the receptacle and closure.

While I herein have shown a single embodiment of my invention for purposes of sufficient disclosure it is evident that changes may be made therein without departure

from the spirit of the invention and within 45 the scope of the appended claims.

Having thus described my invention, what I claim is:

1. In a device of the character described, a vessel having an opening bounded by a 50 vertically extended surface and an adjoining inwardly-inclined, tapering surface; a cover having an overhanging flange and an underlying vertical surface, affording an abutment and a seat for a packing ring respectively; and a packing ring, for insertion on said cover before sealing, adapted to be compressed to a wedge-shaped cross section by contact with the inwardly tapering surface of the jar, the narrower portion of the ring 55 confronting the interior of the jar, the vertical wall of the cover being the other boundary of said ring when sealed.

2. In a device of the character described, a vessel having an opening bounded by a 60 vertically extended surface and an adjoining inwardly-inclined, tapering surface; a cover having an overhanging flange and an underlying vertical surface, affording an abutment and a seat for a packing ring 65 respectively; a packing ring, of rectangular cross section, when not compressed, for insertion on said cover before sealing, adapted to be compressed to a wedge-shaped cross section by contact with the inwardly tapering 70 surface of the jar, the narrower portion of the ring confronting the interior of the jar, the vertical wall of the cover being the other boundary of said ring when sealed, and a notch in said flange terminating inwardly in the plane of said ring seat along 75 which to insert a pin to break the seal.

In testimony whereof I hereunto set my hand in the presence of two witnesses.

GRAY STAUNTON.
